UNITED STATES PATENT OFFICE.

NATHAN BOGGS, OF ROSEBURG, OREGON, ASSIGNOR OF ONE-THIRD TO CREED CONN, OF ROSEBURG, OREGON, AND ONE-THIRD TO HENRY P. CONN, OF MELROSE, OREGON.

EXPLOSIVE-ENGINE.

1,243,483.

Specification of Letters Patent. Patented Oct. 16, 1917.

Application filed April 11, 1916. Serial No. 99,389.

To all whom it may concern:

Be it known that I, NATHAN BOGGS, a citizen of the United States, residing at Roseburg, in the county of Douglas and State of Oregon, have invented certain new and useful Improvements in Explosive-Engines; and I do hereby declare the following to be a full, clear, and exact description of the invention, such as will enable others skilled in the art to which it appertains to make and use the same.

This invention relates generally to engines of the explosive type, and has for its primary object to provide an improved and simplified explosive engine of the two-cycle double acting type embodying a novel construction and arrangement of oscillating cylinders.

Another object is the provision of an improved engine embodying a separate pump or compressor operating in consonance with the engine and connected in a novel manner with the explosive chambers of the engine.

With these and other objects in view, the invention consists in the novel construction, combination and arrangement of parts as will be hereinafter specifically described, claimed and illustrated in the accompanying drawings, in which:

Figure 1 represents a side elevation of the improved engine, partly in section,

Fig. 2 represents a detail sectional view on the line 2—2 of Fig. 1, and

Fig. 3 represents a vertical sectional view through a modified type of engine.

Referring to the drawings, wherein similar reference numerals designate corresponding parts throughout the several views, and referring more particularly to Figs. 1 and 2, wherein is disclosed an engine embodying two cylinders, the numeral 5 indicates a base carrying end and intermediate uprights 6 and 7, respectively, which are arranged in spaced relation and are provided adjacent their lower terminals with bearings 8 and 9, respectively, in which is supported the main crank shaft 10 of the engine. At points intermediate the end and intermediate uprights 6 and 7, the crank 10 is provided with crank pins 11, which are pivotally connected with the piston on connecting rods 12, carrying at their upper extremities the hollow pistons 13. As clearly illustrated in Fig. 1, the crank pins 11 of the crank shaft 55 are opposed.

The upper terminals of the intermediate uprights 7 are forked and provided with bearings 14, which are arranged in axial alinement with the bearings 15 at the terminals of the end uprights 6. The outer 60 bearings 14 of the intermediate uprights 7 and the bearings 15 of the end uprights 6 pivotally support the laterally projecting and diametrically opposed trunnions or stub shafts 16 of a pair of cylinders 17, 65 having heads 18 secured in the upper ends thereof, and heads 19 secured in the lower ends thereof, slidably receiving the piston or connecting rods 12. The upper and lower heads 18 and 19 are provided with spark 70 plug-receiving openings 20 and 21, respectively, and the lower head is provided with the usual stuffing box 22, to prevent leakage of the mixture or explosion around the rods 12.

A double acting pump or compressor cylinder 24 is provided with laterally projecting and diametrically opposed trunnions 25 pivotally supported in the inner bearings 14 of the intermediate uprights 7 and the 80 upper and lower terminals thereof are closed by heads 26 and 27, respectively, the lower head being provided with a stuffing box 28, slidably receiving the piston rod 29 of a piston 30, reciprocably mounted within 85 the cylinder 24. The lower terminal of the piston rod 29 of the pump is provided with a bearing 31, pivotally mounted upon a crank pin 32 adapted to be adjustably secured in a diametrical slot 33 formed in a 90 wheel 34 by a set screw 35. The wheel 34 is non-rotatably secured upon a shaft 36 mounted in a bearing 37 carried by one of the intermediate uprights 7 and is non-rotatably secured to a relatively small gear 95 wheel 38, which meshes with a relatively large gear wheel 39 rotatably secured upon the main crank shaft 10, whereby rotary movement is transmitted to the wheel 34 and, through the crank pin 32, reciprocatory 100 movement is transmitted to the piston rod 29.

The cylinders 17 are partially inclosed by water chambers 40, which communicate with angular passages 41 formed in the outer 105 trunnions 16. Passages 41 are adapted to be connected with a water pipe, not shown, and the heated water is discharged from the water chambers 40 through ports 42, arranged above the passages 41 in the trun- 110

nions 16 and adapted for connection with a flexible water pipe.

The chamber 40 is partitioned to provide mixture inlet passages 43, which communicate centrally with passages 44 formed in the inner trunnions 16 of the cylinders 17 and communicate at their outer ends with substantially U-shaped pipes 45. The cylinder heads 18 and 19 are provided with inlet ports 46 and 47, respectively, which communicate with the inlet pipes 45 and are inclosed by valve housings or casings 48, receiving the inlet valves 49. The valves 49 are of the outwardly closing puppet type and the stems thereof are slidably received within guides 50, and are normally retained in closed position by the tension of springs 51 coiled about the stems and engaged with the guides 50.

Mixture conducting pipes 52 are secured in the inner trunnions 16 of the cylinder 17 and are rotatably received in the passages or bores 53 formed in the trunnions 25, whereby the explosive charge, under compression, is conducted from the pump cylinder 24 to the combustion chambers of the cylinders 17, the rotatable connection between the pipes 52 and the trunnions 25 permitting the variable oscillatory movement of the engine and pump cylinders 17 and 24, respectively. The passages 53 communicate with oppositely extending passages 55 formed longitudinally of the opposite sides of the cylinder 24, and connect by ports 56 with the opposite ends of the pump cylinder. The combustible gas or fuel to be compressed and delivered to the engine cylinders 17 by the pump 24 is admitted to the latter by a pipe or manifold 57, which is connected with a suitable carburetor, not shown, and communicates with inlet ports 58 in the heads 26 and 27 of the cylinder. The discharge of the combustible gas through the ports 58 is prevented by a pair of spring actuated check valves 59 arranged in the ports 58 and mounted in guides 60. The expanded products of combustion resulting from the intermittent and alternate explosions in the opposite ends of the cylinders 17 are discharged through exhaust ports 61, formed centrally of the cylinders 17 and adapted to be uncovered by the pistons 13 during reciprocatory movement thereof.

As above stated, the pistons 13 of the engine cylinders are of hollow formation and are effectively cooled by air admitted thereto through ports 62 formed longitudinally in the piston rods 12 and communicating with ports 63 formed in the connecting rod bearings.

Due to the gear ratio of the gears connecting the main shaft 10 with the shaft 36, it is evident that the piston 30 of the pump or compressor reciprocates at a greater

speed than the pistons 13 of the two cylinders 17, and thus during operation of the engine the combustible gas is alternately pumped into the opposite combustion chambers of the two cylinders. It is further evident that due to the fact that the two engine cylinders operate in the manner of a double acting two cylinder engine four power impulses are imparted to the crank shaft 10 at each revolution of the latter. The pressure at which the combustible gas is delivered to the respective cylinders 17 may be varied as desired by changing the stroke of the piston 30 of the pump or compressor. This adjustment is effected by moving the crank pin 32 longitudinally within the slot 33, and subsequently locking it in adjusted position by the set screw 35.

In the modification of the invention illustrated in Fig. 3 there is disclosed an explosive engine embodying but one cylinder and a pump or compressor associated therewith for delivering combustible gas to the engine cylinder during operation. This type of engine is also of the two cycle double acting type and the fundamental features of construction are identical with the type illustrated in Figs. 1 and 2. Referring to the modification in detail, the numeral 5^a indicates a base carrying spaced vertical end and center uprights 6^a and 7^a, respectively. Adjacent their lower ends the uprights 6^a and 7^a are provided with main bearings 8^a and 9^a, respectively, in which is rotatably supported the crank shaft 70.

The upper terminals of the uprights 6^a and 7^a are provided with bearings 71 in which are pivotally supported the diametrically opposed trunnions 72 of the single engine cylinder 73. One of the trunnions 72 is provided with a water inlet pipe 74, which connects with the water chamber 75, the water contained in the chamber 75 being discharged, during operation of the engine through a flexible water outlet pipe 76. The other trunnion 72 is provided with a passage 77, which communicates with an inlet passage 78 formed in the cylinder 73 and which latter communicates at its opposite ends with inlet pipes 79. The pipes 79 are connected with the inlet ports 80 formed in the heads 81 of the cylinder 73 in which are arranged outwardly closing inlet valves 82. An inlet pipe 83 is secured in the passage 77 of the trunnion 72 and is rotatably received within an axial passage 84 formed in the adjacent trunnion 85 of the pump or compressor cylinder 86. The trunnions 85 are pivotally supported in the bearings 71 of the uprights 6^a and 7^a, and the passage 84 communicates with a longitudinal passage 87 formed in the wall of cylinder 86. The passage 87 communicates with the opposite ends of the cylinder 86, whereby the combustible gas compressed in the ends of

the cylinder 86 during operation of the engine is conducted to the combustion chambers of the engine cylinder 73. Check valves 87^a are arranged at the opposite ends 5 of the passage 87 and are designed to prevent the combustible gas reentering the ends of the pump cylinder 86 subsequent to a compression stroke of the piston 91, which latter is reciprocably mounted in the cylinder.

10 The combustible gas or fuel is admitted to the ends of the cylinder 86 through passages 88 and 89 formed in the trunnion and cylinder walls 85 and 86, respectively, and pipes 15 90, which communicate with the valve controlled inlet ports 91 in the heads of the cylinder 86.

15 The piston 91^a is reciprocably mounted within the cylinder 86 and is connected with a piston rod 92, which latter is pivotally connected at its lower end with an adjustable 20 crank pin 93 carried by a wheel 94. The wheel 94 is non-rotatably supported upon a shaft 95, which is connected with the crank 25 shaft 70 of the engine by pinions 96. The shaft 95 may be connected by gears 97 with a high tension magneto 98 for furnishing 30 electricity for the ignition system (not shown) of the engine.

35 The engine cylinder 73 is provided with an exhaust port 99 over which is movable the hollow piston 100, carrying the piston rod 101, which is connected at its lower terminal with the crank pin 102 of the crank

40 shaft 70.

As in the type of engine illustrated in Figs. 1 and 2, the hollow piston 100 communicates with a longitudinal bore 103 formed in the piston rod 101, whereby air is admitted to the interior of the piston 100, during operation of the engine, for effectively cooling the latter.

What I claim is:

1. In an explosive engine, a cylinder hav-

ing an internal circumferential chamber, a 45 pair of laterally projecting hollow trunnions carried by said cylinder, one of said trunnions communicating with said chamber, partitions arranged in said chamber providing a mixture conducting passage 50 communicating with the other hollow trunnion, said cylinder having inlet ports in the ends thereof, and pipes connecting said mixture conducting passage with said inlet ports.

55

2. In an explosive engine, a cylinder having an internal circumferential chamber, pairs of laterally projecting hollow trunnions carried by said cylinder, partitions arranged in said chamber dividing the latter 60 into mixture-conducting and water containing passages, one of said passages communicating with one of the hollow trunnions and the other passage communicating with the other hollow trunnion, said cylinder having 65 inlet ports in the ends thereof, and pipes connecting said mixture-conducting passage with said ports.

3. In an explosive engine, a plurality of uprights, a pump cylinder pivotally supported in said uprights, an engine cylinder pivotally supported in said uprights, means connecting said pump cylinder with said engine cylinder, a piston reciprocably mounted in said engine cylinder, means connecting 70 said piston with said crank shaft, a piston reciprocably mounted in the pump cylinder, a wheel operatively connected with the crank shaft, an adjustable crank pin connected with the wheel, means for securing the crank pin 75 in adjusted position, and means for connecting the crank pin with the pump piston.

In testimony whereof I affix my signature in presence of two witnesses.

NATHAN BOGGS.
